HERMAN J. HAMMERLY, OF WALLINGFORD, CONNECTICUT, ASSIGNOR TO THE TRUMBULL ELECTRIC MANUFACTURING COMPANY, OF PLAINVILLE, CONNECTICUT, A CORPORATION OF CONNECTICUT

ELECTRIC SWITCH

Application filed July 29, 1930. Serial No. 471,471.

My present invention relates to certain improvements in the construction and operation of electric circuit breaking switches of the type which are usually enclosed in protective casings or boxes and provided with external operating handles, this type of switch being commonly known as "enclosed switches".

My invention relates particularly to the combination of elements for the making and breaking of the circuit in a novel and efficient manner.

The principal object of my invention is to provide a very compact and efficient switching means for breaking the circuit at 15 four points in each leg of the circuit to be controlled.

Another object is to provide a switch having centrally pivoted blades so arranged as 20 to be specially well adapted for operation by a correlated quick-make and quick-break means.

Another object is to provide a switch construction in which the movable blades are 25 loosely mounted to provide for a self-adjusting spring engagement with the correlated stationary contacts.

Another object is to provide a switch construction in which the blades move away 30 from the stationary contacts in two directions during the arcing possibility period of movement.

Another object is to provide a switch having a pair of movable blades arranged to 35 form substantially a split pivoted disc and to cause the same to engage the stationary contacts with a self-adjusting, rotary wiping contact.

Another object is to provide a switch having reversible stationary contacts which may 40 be inspected or removed from the front of the switch without disturbing other correlated elements.

Another object is to provide a switch construction in which the movement and correlation of the contacts is such that a fresh 45 and comparatively cool portion of the movable contact is constantly presented at the possible arcing point or, in other words, so that the arcing point of the movable con-

tact is constantly changed during the circuit opening movement of the switch.

Another object is to so design and operate the contacts of a switch that, during the possible arcing period of the switch movement, 55 a movable contact of flat and comparatively heavy metal will move only a comparatively short distance away from the stationary contact so as to function as a baffle to the arc by limiting the open air space between the 60 movable and stationary contacts.

Another object is to provide a switch in which the contacts can not be stuck or 65 frozen together as is possible in the usual knife blade type of switch.

Fig. 1 is a front view of the switch embodying the improvements of my invention, the parts being shown in the open circuit position and the cover of the box being open 70 and broken away.

Fig. 2 is a transverse sectional view of the same.

Fig. 3 is a side view of the switch plug and contact mechanism, the shaft being shown 75 in section.

Fig. 4 is a longitudinal sectional view.

Fig. 5 is an exploded prospective view showing parts of the switch mechanism.

Fig. 6 is a view showing the parts in one 80 of the positions they occupy while breaking the circuit.

The switch base 10 is preferably of suitable molded insulation and it can be secured in a box 11 by one or more screws 12 in the usual manner.

The switch may be designed to take care of any number of circuits or poles of a circuit, as for instance, a switch for controlling a double pole circuit as herein shown. It will only be necessary, however, to describe a single unit. The stationary contacts 15 and 16 are secured to the base, for instance, by screws such as 17 and provided with circuit terminals such as 18. Preferably these contacts 15 and 16 are oppositely arranged, 90 one being above the axis of the main shaft 19 and the other below. The main shaft is supported in suitable bearings in base so as to permit it to oscillate. For this purpose any suitable form of actuating mechanism 95 100

may be employed as for instance the external handle 20 with the internal throwing spring 21, and rocker arm 22 actuated by the handle through a lost motion connection. The 5 plate 23 is secured on the end of the shaft 19 and has an extension pin 24 co-acting with the rocker 22.

The movable blades 26 and 27 are preferably in the form of semi-circular plates 10 which are mounted on a square hub 28 on the disc 29 which is slidably mounted on the shaft 19 and has a sleeve 30 which slides in a bearing 31 in the post 32 which is a part of the base. A second disc 33 is also slidable 15 on the shaft 19 and is pressed by the spring 34 toward the switch blades 26 and 27.

Pins 35 and 36 are carried by the disc 28 and have shanks which extend into openings 20 37 and 38 in the plates 26 and 27. These pins 35 and 36 co-act with inclined cam-like shoulders 39 and 40 and with stop shoulders 41 and 42. The discs 28 and 33 are of insulating material.

In the closed circuit position a spring 34 25 holds the switch blades pressed against stationary contacts 15 and 16. It will be seen that each of the blades or plates 26 and 27 carries only one-half of the current. To open the circuit the switch handle 20 is pulled 30 down and the shaft 19 rotated counter-clockwise as viewed in Figures 3 to 6. This rotative movement causes the pins 35 and 36 to ride up the inclined surfaces 39 and 40 very quickly after rotative movement has 35 been started. The inclines 39 and 40, however, do not begin at the shoulders 41 and 42 but a certain clearance is left so that the contact plates rotate through a considerable angle before they begin to move away from 40 the stationary contacts. The result is that when the circuit is broken the switch blades are not only rotating in the plane of the stationary contact faces but they are also traveling longitudinally of the shaft 19 away 45 from the stationary contacts thus effecting a break at each end of each of the movable switch blades as they separate from the respective stationary contacts. This compound action serves as a very effective 50 method of interrupting the arc and preventing injury to the contacts and the switch parts.

At the moment of breaking the circuit, the tip 43 of plate 26 is still in full contact with 55 contact 16 and the tip 44 of plate 27 is still in full contact with contact 15, thus the tendency of the arc would be to jump from contact 15 to tip 45, from contact 16 to tip 46 and from plate 26 to plate 27 along the 60 lines of separation but as the opening movement continues, plates 26 and 27 move laterally away from contacts 15 and 16 thus making two more breaks or four in all.

The rotary movement of the plates 26 and 65 27 causes a fresh portion of the plates to be

brought into the possible arcing area, or in other words, the arcing point of the plates is changed constantly during the opening movement of the switch.

When the circuit is closed the action occurs in the reverse direction so that the contacts are brought together with a sliding and snap action thus keeping the contact surfaces bright and free of corrosion or carbon.

The switch blades 26 and 27 are more or less loosely mounted on the shaft 19 so that they are able to adjust themselves to the stationary contact surfaces and thus provide substantial and perfect contact even though the stationary contacts may be slightly out of alignment. The convex bearing surfaces of the stationary contacts also aid in providing perfect contact.

I have shown a latch 50 of a typical form for holding the cover closed and it will be understood that interlocking mechanism might be employed as is commonly done in enclosed switch constructions.

I claim:

1. An electric switch including an insulating base having a post projecting at substantially right angles thereto and having a stop shoulder with an inclined approach, a pair of stationary contacts mounted on opposite sides of said post, a rotatable shaft supported in said post between said stationary contacts, a switch member rotatably carried by said shaft and slide longitudinally thereon toward and from the post, and means for rotating said shaft and switch member and moving said switch member longitudinally of the shaft as it is rotated, including a spring for pressing the switch member toward the stationary contacts and a projection coacting with the inclined approach for moving the switch member away from the contacts as the switch member is rotated.

2. An electric switch comprising an insulating base having projecting posts, a shaft rotatably supported in said posts, stationary contacts mounted on opposite sides of one of said posts, a rotatable switch member mounted to slide on said shaft toward and from said contacts, a spring interposed between one of said posts and said switch member for moving the switch member toward the contacts and means including a manually operable member for rotating said shaft and switch member and moving said switch member away from said contacts.

3. An electric switch including an insulating base, a pair of stationary contacts mounted on said base, a relatively vertical insulating support having stop shoulders and inclined surfaces, a shaft extending through said support and rotatable therein, an insulating carrier mounted on said shaft, a pair of spaced contact plates carried by said insulating carrier, and projecting members

- carried by said insulating carrier and co-acting with said inclined surfaces and said stop shoulders.
4. In an electric switch an insulating support, a shaft carried by the support, stationary contacts mounted one on each side of said shaft, said support having a stop shoulder with an inclined approach, an insulating carrier rotatable with said shaft and slideable thereon and having a projection adapted to coact with said shoulder and said inclined approach, a switch member carried by said carrier and adapted to engage said contacts, a spring arranged to force said carrier so that the switch member is resiliently pressed toward said contacts, and snap action mechanism coacting with said shaft to rotate the shaft and switch member, said stop shoulder serving to limit the rotation of the switch member toward the closed circuit position and the inclined approach and projection coacting to retract the switch member when moving the switch to the open circuit position.
5. In an electric switch, a pair of spaced apart stationary contacts, a rotatable shaft, a switch member carried thereby and adapted to close the circuit through said contacts, a spring for forcing said switch member toward said contacts, a cam, means coacting therewith to move the switch member laterally away from the contacts when the switch member is rotated, snap action mechanism having a lost motion connection with the shaft for rotating the shaft and switch member for closing and opening the circuit with a snap action, and means for supporting the contacts and the shaft and snap action mechanism.
6. In an electric switch, an insulating base, a pair of stationary switch contacts mounted on said base, a rotating shaft mounted on said base between said contacts, an insulating carrier mounted to rotate with said shaft, two rigid semi-circular spaced apart switch plates mounted on the insulating carrier in a common plane and rotatable with said carrier, snap action and cam mechanism for simultaneously rotating said insulating carrier and said plates and moving said plates laterally with respect to said stationary contacts as said shaft is rotated, and a spring separate from the snap action mechanism for pressing the insulating carrier in the direction of said contacts.
7. In a switch, a pair of stationary contacts having convex contact surfaces, a pair of rigid flat semi-circular rotatable switch plate contacts spaced apart from each other and having their ends engageable simultaneously with said stationary contacts so that each plate contact carries only one-half of the current, mechanism for simultaneously moving said rotatable contacts rotarily and laterally away from the said stationary contacts, and a spring separate from said mechanism for pressing the plate contacts toward the stationary contacts.
